UNITED STATES PATENT OFFICE

FREDERICK KLEIN, OF BROOKLYN, NEW YORK

WINDOW SASH

Application filed August 9, 1928. Serial No. 298,495.

This invention relates to windows and pertains more especially to the sashes thereof.

One object of the invention is the production of new and improved window sashes which can be readily substituted for those already in use.

Another object is to provide a simple and efficient sash having glass panes which can conveniently be cleaned on both sides from within the room.

A further object resides in providing a sash the component parts whereof can readily be separated or firmly locked together and which when so locked will effectively prevent the entrance of rain, snow or sleet, enabling besides, moisture deposited on the structure to quickly drain off.

A still further object is to produce a construction as above enumerated permitting access to the interior of the sash for inspection, painting, and repair, and capable of being produced in wood, metal or sheet material and in which the parts when assembled in their normal position will not rattle.

Further and more specific objects, features, and advantages will more clearly appear from the detailed description given below taken in connection with the accompanying drawings which form part of the specification, which illustrate one embodiment of the invention, wherein:—

Figure I is a fragmentary elevation of the improved construction, looking from the inside of the room, both sashes being shown in closed position;

Fig. II is a fragmentary vertical section taken on the line II—II of Fig. I looking from right to left as denoted by the arrows;

Fig. III is a fragmentary vertical section taken on the line III—III of Fig. I looking from right to left, the outer sash being raised and the parts of the lower inner sash shown in displaced position the one relatively to the other;

Fig. IV is a view similar to the preceding, with one of the displaced elements of the lower sash shown in tilted position;

Fig. V is a similar view to Fig. III with conditions reversed, namely, the upper outer

sash being in the lowered position and the parts thereof interrelatively displaced;

Fig. VI is a view corresponding to Fig. V showing one of the displaced elements of the upper sash in tilted position;

Fig. VII is a horizontal section taken on the line VII—VII of Fig. I looking downwardly;

Fig. VIII is a horizontal section on the same line showing one of the parts of the sash in the tilted position;

Fig. IX is a fragmentary perspective view of the upper sliding sash, the tilting sash member being removed;

Fig. X is a fragmentary perspective view of the tilting sash alone;

Figs. XI, XII and XIII are horizontal sections taken respectively on the lines XI—XI, XII—XII, and XIII—XIII of Fig. X looking downwardly in the direction indicated by the arrows;

Figs. XIV, XV, and XVI are fragmentary perspective detail views of the parts composing the upper right hand corner of Fig. X;

Fig. XVII is an enlarged fragmentary detail view of the lower left hand corner of Fig. I showing the sliding and tilting sash in locked position;

Fig. XVIII is a view similar to Fig. XVII, the same parts being shown in displaced position relative to each other;

Fig. XIX is a similar view to Fig. XVIII, the tilting sash being omitted;

Fig. XX is a vertical section on the line XX—XX of Fig. XIX looking from the right to the left;

Fig. XXI is an enlarged fragmentary view of the lower left hand corner of Fig. I showing the tilting sash alone; and

Fig. XXII is a side view of Fig. XXI looking from the left to the right.

In the preferred form of invention illustrated in the accompanying drawings, the reference letter A represents the right hand side member of the window casing, and B the left hand side member of the same casing. C¹ denotes the inner guide in member A and may consist of a groove as shown. C² is the outer guide in said member A, D¹ the inner

guide in member B and D² the outer guide in the last named member.

E¹ represents the sill of the window casing, and E² the sub-sill thereof. E³ designates the trim for the sill E¹ on the room- or in-side of the window casing. E⁴ refers to the trim for the sub-sill E² on the room or inner side. F¹ is the upper top member of the window casing and F² is the lower top member of the same casing. G¹ is the right hand pulley housing for the lower sash, G² being the left hand pulley housing for the same sash, and G³ one of the pulley housings for the upper sash.

H¹ is the right hand counter weight for the lower sash, H² the left hand counter weight for the same sash, H³ and H⁴ the left and right hand counter weights for the upper sash. J¹ is a weather strip for the lower sash and J² a similar strip for the upper sash. K¹ is a window pane for the upper sash, and K² is a window pane for the lower one of said sashes.

The upper-outer sash member is designated 25 as a whole by numeral 25, and is composed of right and left hand stiles 26^a and 26^b having formed thereon ribs 27^a and 27^b respectively which are engageable with the guide grooves C², D². The upper extremities of stiles 26^a 30 and 26^b are bi-furcated as at 28^a and 28^b to afford clearance spaces in and between which are anchored one end each of chains or cords the other terminals whereof are attached to the counterweights H³ and H⁴. The lower 35 ends of the stiles 26^a and 26^b are provided at their inner faces with sidewise and outwardly flaring recesses 29^a and 29^b of which the left hand one is visible in Figs. IX, and XVII—XXII. These recesses are covered up by a 40 lower cross rail 30^a preferably of angular formation and affixed to the inner or room side of the stiles 26^a and 26^b. 31^a and 31^b are upper inner and outer top rails secured to the said extremities of the stiles 26^a and 26^b on 45 the opposite sides of the bifurcations 28^a and 28^b, leaving a space 32 therebetween, hereinafter more fully referred to.

33^a and 33^b respectively denote right and left hand lip-strips projecting inwardly in 50 opposed relation from the inner or room faces of the stiles 26^a and 26^b and extend upwardly a certain distance from the upper edge of the cross rail 30^a. From the outer faces of the last named stiles extend in opposed relation, inwardly, similar right and left hand strips 34^a and 34^b commencing at points adjacent the lower edge of top rail 31^b and extend downwardly a given distance therefrom. From Fig. II it will be seen that 55 the upper and lower transverse ends of strips 33^a and 34^a terminate substantially in the same horizontal plane. Thus it will be seen that the above mentioned members which jointly compose the outer sash 25 are immovably secured together to form a rigid frame.

The part of the upper outer sash member which is tiltable within the sliding one just described is referred to in its entirety by the numeral 50 and consists of right and left stile members 51^a and 51^b respectively. The opposed inwardly turned sides of these members are rabbeted as indicated at 51^c for 51^a, and at 51^d for 51^b, to afford receiving ledges or grooves for the upper window pane K¹. Overlying the outwardly or exteriorly facing narrow portion of stiles 51^a and 51^b are right and left glass retaining strips 52^a and 52^b respectively. The lower extremities of the stiles 51^a and 51^b are undercut as seen most clearly at 53^a on the right hand side of Fig. X, in order to receive an inner lower cross rail 54^a. The latter is rabbeted as at 54^b to form a continuation and lie in the same plane with the rabbets 51^c and 51^d to continue the glass retaining ledge. The glass retaining strip at the bottom of the tilting sash is indicated by the numeral 54^c.

Against the undersides or bottom faces of the cross rail 54^a and strip 54^c abuts another strip 55^a of the same width as those last referred to. From the opposite outer end portions of the strip 55^a project sidewise outwardly therefrom right and left horns 55^b and 55^c. The exteriorly turned faces of these horns are bevelled as will be seen to best advantage at 55^d on the lower right hand side of Fig. X. The bevels of horns 55^b and 55^c afford easy entrance and engagement into and with the straight outer or rear walls of recesses 29^a and 29^b. In a like manner the straight or perpendicular ends of said horns 55^b and 55^c co-act with the inclined side walls of the recesses 28^a and 29^b to locate or centralize the lower portion of tiltable sash member 50 within the sliding sash member 25.

The upper extremities of stiles 51^a and 51^b are reduced in width so as to leave shoulders and tenon-like projections 51^e and 51^f thereon respectively right and left. A top cross rail member 56^a is attached by its outer reduced end portions to the inner or room faces of the tenons 51^e and 51^f, which member 56^a in conformity with the stiles 51^a, 51^b and 54^a, is provided with a glass pane receiving rabbet 56^b. The glass retaining strip 56^c is affixed to the exterior of said tenons 51^e and 51^f and the combined thickness of members 56^a and 56^c is of such dimensions as to have a sliding fit in a vertical direction in and through the space 32 previously referred to.

Lip strips 57^a and 57^b respectively right and left, are secured to the upper half of the inner room faces of the stiles 51^a and 51^b and overhang the latter outwardly sidewise to an extent equal to the width of the stiles 26^a and 26^b of the sliding sash. Other lip strips 58^a and 58^b respectively right and left are fastened to the lower outer faces of stiles 51^a and 51^b and reach sidewise outwardly beyond the same an amount equal to the overhanging 130

width of the before named strips 57^a and 57^b, being also flush with the inner side edges of the glass retaining strips 52^a and 52^b. A filling strip 54^d of a depth equal to that of the strips 54^a or 54^c and 55^a is affixed to the exterior faces of the latter and 54^c, projecting sidewise beneath the overhanging portions of the lip strips 58^a and 58^b. The last named strips extend upwardly along stiles 52^a and 52^b to a level somewhat below the lower ends of the lip strips 57^a and 57^b. The distances between the top ends of strips 58^a and 58^b, and bottom ends of lip strips 57^a and 57^b are approximately equal to the fore and aft thickness of the stiles 26^a and 26^b plus a suitable clearance to enable the member 50 to be freely tilted into the position illustrated by Fig. VI. When so tilted the innermost inwardly turned end portions of strips 57^a and 57^b rest and are supported upon the upper transverse ends of lip strips 33^a and 33^b pertaining to the sliding sash while the upper ends of lips 58^a and 58^b on the tilting sash abut the outer exterior faces of the stiles 26^a and 26^b directly beneath the lower transverse ends of the lip strips 34^a and 34^b of the sash 25. From the foregoing, it is evident that the before named members composing the inner sash 50 are unyieldably secured one to the other to form a frame which is rigid.

The position assumed by sash 50 when the same is tilted back or vertically, is indicated in Fig. V wherein is represented the displaced condition of said sash 50 relatively to the other sash 25, i. e. into the plane of movement of the last named sash member. To bring the tiltable sash member 50 into register with or in planar alignment with the upper right hand portion of Figs. III and IV, so that rails 56^a and 56^c are received within the space 32 and horns 55^c and 55^d enter recesses 29^a and 29^b, it becomes necessary to lift sash 50 with respect to the sash member 25, at which time the upper transverse edges of lip strips 58^a and 58^b abut the lower similar edges of strips 34^a and 34^b on the sliding sash, both sets of these edges being bevelled downwardly and rearwardly so as to shed rain and moisture.

The means for locking the sash member 50 in its highest position within the member 25, consists as depicted in Figs. I and VI of latches 60 pivoted at 61 to the inwardly facing sides of the inner lip strips 33^a and 33^b of said member 25. At such times as these latches are in locking position they fit snugly in between the upper transverse ends of strips 33^a and 33^b and the lower similar ends of lip strips 57^a and 57^b, thus acting as struts or braces in preventing the member 50 from dropping down. When it is desired to displace the member 50 relatively to the member 25, the said latches 60 are swung downwardly

and inward in the plane of the sashes into the horizontal position illustrated by Figs. I and VIII.

A grip or operating knob 62 is provided for the manipulation of each of the latches 60. It will be noted that the corners of the latches are rounded as at 60^a and 60^b to afford clearance and ease of movement into and out of locking position.

Both of the lower-inner and outer-upper sashes are alike except that the positions of cross rails 30^a and 30^b are reversed. As shown, the upper rail 30^a is affixed to the lower inner sides of the stiles 26^a and 26^b while the other cross-rail 30^b is secured to the upper and outer sides of the stiles of the lower inner sash. When the lower inner and upper outer sashes are in the closed position depicted in Figs. I and II rail 30^b overlaps and is contacted at the underside thereof by cross-rail 30^a. The locking device which clamps the sashes together is composed of the usual parts 62^a and 62^b of which part 62^a is carried by rail 30^a and part 62^b by the other rail 30^b. The numerals 63^a and 63^b denote operating handles of which handle 63^a is attached to rail 30^a while the other handle 63^b is fixed to the rail 30^b.

In describing the operation of the device, it will be assumed that the parts are in the position shown in Fig. II and that it is desired to clean the glass of the tiltable member 50. In this case the latches 60 are operated to release the tiltable from the slidable member and then the lock 62^a—62^b is operated to disconnect the upper from the lower sash. The latter sash is then pushed upward while the upper sash is moved down into the position shown in Fig. V. With the latches 60 released, the slidable member 25 is pulled upward slightly to displace it with respect to the tiltable member 50. The last named member can then be swung to the position shown in Fig. VI and both sides of the glass pane washed and cleaned or reached for purposes of repair or replacement, from the inside of the room. The same operation in general will take place when the lower sash is to be manipulated to open the pane-carrying portion thereof. When the cleaning, repairing or other operations are completed, the tiltable member is swung back into the plane of the slidable member and then they are moved relative to each other in the same plane to bring the one into engagement with the other. The coacting bevelled or sloping surfaces before referred to when engaged will tend to keep the two portions of the sash together and prevent their rattling. The latches 60 will hold them in their normal position, one nested or housed within the other. It will be noted that there is no positive connection between the two portions of each sash and consequently there is no hardware required except the latches and the lock 62^a.

In further considering the invention in its general aspects, it will therefore be observed that it comprises sashes each having a slideable member and a tiltable member, the latter normally housed or nested within the former and capable of being withdrawn from its normal position by movement in the plane of the sliding member at which time the construction will permit it to be swung at a wide angle in order to be accessible for the purposes above specified. The sloping engaging surfaces of the co-operating portions will cause them to fit snugly and tight when engaged and prevent rattling as well as to preclude admission of rain or other moisture.

While I have described my improvement in detail with respect to a preferred form thereof, I do not desire to be limited to such details or form since changes and modifications may be made and the same embodied in other forms without departing from the spirit and scope of the invention in its broader aspects. Hence I desire to cover all modifications and forms coming within the language of any one or more of the appended claims.

Having described my invention what I desire to secure by Letters Patent and claim is:—

1. A window sash comprising a slideable member and a tiltable member, normally engaged and disposed in the same plane, means permitting said tiltable member to be moved in the same plane and with respect to said slideable member to disengage it therefrom, and means enabling the tiltable member to be swung at an angle to the slideable member when disengaged.

2. A window sash comprising a slideable member and a tiltable member, the latter normally nested or housed within the former, said members having co-operating grooves and ribs to facilitate nesting thereof, co-acting sloping engaging surfaces on the members to effect a tight nesting of the same, and means to latch the members in their nested position, one of said members being movable in the plane of the other to disengage it therefrom, said member being capable of tilting at an angle to the other when disengaged.

3. A window comprising a casing, a sliding sash guided thereby and composed of spaced apart rail sections and recessed stiles, another sash tiltably mounted on said first named sash and including upper and lower rail elements, the upper one of said elements being adapted to enter the space between said rail sections, the lower element of said other sash having bevelled extensions capable of being received in the recesses of said stiles at such times as the sashes are placed in closed position and to withdraw from said recesses when the said other sash is to be tilted relatively to said sliding sash.

4. A window comprising a casing, a sliding sash guided thereby, a tiltable sash co-

operating with the first sash, and face strips mounted on said sliding sash, said tiltable sash being of less width than the sliding sash and adapted to swing therein and relatively thereto, said strips coacting to limit the swing of the tilting sash and to support the same when in tilted position.

5. A window comprising a casing, a sliding sash guided therein, a tilting sash carried by the first mentioned sash, coacting lip strips affixed to said sashes so as to overlap one from the other thereof, the adjoining ends of said strips being in spaced relation when the sashes are in closed position, and means connected to said sliding sash disposed in said space and serving to lock the said sashes together in the last named position.

6. A window sash comprising a slideable member and a tiltable member both of which are rigid, the tiltable member being normally nested or housed within the slideable member, locking means for holding said members together, means enabling said tiltable member to be displaced in one direction from the slideable member, and means permitting the tiltable member when thus displaced to be swung at an angle to said slideable member while the latter is in its original position.

7. A window sash comprising a slideable member and a tiltable member both of which are rigid, the latter capable of being nested or housed within the former, said members having immovable guiding surfaces thereon to facilitate nesting thereof, and fixed co-acting engaging surfaces on the members serving to effect tight nesting of the same.

8. A window sash comprising a slideable member and a tiltable member normally nested together and each of which is a rigid entity, means permitting said tiltable member to be moved in one direction relatively to the other member to un-nest them, and means permitting the tiltable member to be swung with respect to the other at an angle when thus moved.

9. A window sash comprising a slideable member and a tiltable member normally nested or housed together, each of said members being of rigid construction, means permitting said tiltable member to be moved relatively to the other in one direction to un-nest them, means enabling the tiltable member to be swung at an angle with respect to the other when thus moved, and co-operating surfaces at the lower and outer ends of said members engageable when they are nested to hold them snugly together and prevent rattling thereof.

10. A window sash comprising a pair of normally or housed members each of which is rigid, means permitting one of said members to be moved relatively to the other in one direction to un-nest them, means enabling said members to be swung at an angle with respect to the other when thus moved, co-operating surfaces at the lower and outer sides of said

members engageable when they are nested to hold them snugly together, and pivoted means for latching the members in their nested condition.

- 5 11. A window sash comprising a pair of normally nested or housed members each of which is rigid, means permitting one of said members to be moved relatively to the other in one direction to un-nest them, means enabling said member to be swung at an angle with respect to the other when thus moved, and co-operating bevelled surfaces at the lower ends of said members engageable to centralize them both sidewise and widthwise into nested condition.
- 10 12. A window sash comprising a pair of normally nested or housed members both of which are rigid, means permitting one of said members to be moved relatively to the other in one direction to un-nest them, means enabling said member to be swung at an angle with respect to the other when thus moved, co-operating sloping surfaces at the lower and outer sides of each of said members engageable both sidewise and widthwise to urge them together in nested condition, and means to lock the members in such condition, said last named means being arranged to swing towards the middle of the members when releasing the same.

FREDERICK KLEIN.
